SANDAL

John B. Reinhart, Jr., and Joseph B. Ruebel,
Farmington, Mo.

Application October 17, 1949, Serial No. 5,538

Term of patent 7 years

(Cl. D7—7)

To all whom it may concern:

Be it known that we, John B. Reinhart, Jr., and Joseph B. Ruebel, citizens of the United States, residing at Farmington, Missouri, have invented a new, original, and ornamental Design for Sandal, of which the following is a specification, reference being had to the accompanying drawings, forming part hereof.

We claim:

The ornamental design for a sandal, substantially as shown and described.

JOHN B. REINHART, JR.
JOSEPH B. RUEBEL.
